Patented Jan. 7, 1919.

2 SHEETS—SHEET 2.

UNITED STATES PATENT OFFICE.

BARNIE B. McENTIRE, OF IRMO, SOUTH CAROLINA.

LOCOMOTIVE REVERSING DEVICE.

1,290,265.

Specification of Letters Patent.

Patented Jan. 7, 1919.

Application filed February 6, 1918. Serial No. 215,616.

To all whom it may concern:

Be it known that I, BARNIE B. McENTIRE, a citizen of the United States, residing at Irmo, in the county of Lexington, State of South Carolina, have invented a new and useful Locomotive Reversing Device; and I do hereby declare the following to be a full, clear, and exact description of the invention, such as will enable others skilled in the art to which it appertains to make and use the same.

This invention relates to an improved reversing device for steam locomotives, and one of the objects of the invention is to provide a simple and efficient device of this kind in substitution for the hand operated mechanism for operating the link motion on a steam locomotive.

A further object of the invention is to provide an improved combined pneumatic and hydraulic reversing device for locomotives, in substitution for the hand operated mechanism, thereby relieving the severe strain on the locomotive engineer.

25 A further object of the invention is to provide a simple, efficient, improved and practical device of this kind having improvements over the Patent No. 1,248,857, issued Nov. 27, 1917 to B. B. McEntire.

30 In practical fields the details of construction may necessitate alterations falling within the scope of what is claimed.

The invention comprises further features and combination of parts as hereinafter set forth shown in the drawings and claimed.

In the drawings:—

Figure 1 is a longitudinal sectional view through a supporting frame (which may form a part of the locomotive), showing the improved reversing device as applied to the link motion mechanism.

Fig. 2 is a longitudinal sectional view through the pneumatic and hydraulic reversing device.

45 Fig. 3 is a plan view of the same.

Fig. 4 is a transverse sectional view on line 4—4 of Fig. 2.

Referring more especially to the drawings, 1 designates the link motion as a whole, 50 and 2 denotes a bell crank lever of said link motion, and to one arm of said bell crank lever a pitman 3 is pivotally connected as at 4. Mounted in a frame 5 which may con-

stitute a part of the locomotive is the base 6 of a cylinder 7, in which a piston 8 is mounted to reciprocate. Suitable piston heads 9 and 10 are connected to the ends of the cylinder 7 by suitable bolts 11. The cylinder head 9 has a packing box or gland 12, through which the piston rod 13 (which is connected to the piston 8) passes. This piston rod is mounted and guided in a suitable bearing 14, and is in turn pivoted at 15 to the pitman 3. Rising upwardly from the cylinder 7 is a combined pneumatic and hydraulic chest 16. This chest consists of the upper and lower sections 17 and 18, the flanged parts of which are bolted together by the bolts 19. The bottom 20 of the upper section constitutes a division or a partition 70 between the upper and lower sections of the chest. A partition wall 21 extends transversely of the lower section, thereby dividing the lower section into a pair of hydraulic chambers 22 and 23. The upper section is provided with a pneumatic chamber 24, and connected to the top 25 of the section 17 is an air or pneumatic pipe 26. This pipe 26 is designed to be connected to the usual air or pneumatic cylinder or tank 80 (not shown) of the pneumatic system of the train, and is in turn in communication with the pneumatic chamber 24. The top 25 is secured by the bolts 27 to the section 17. The bottom of the section 17 or the 85 partition between the pneumatic chamber 24 and the hydraulic chambers 22 and 23 is provided with a valve bearing 28, which is substantially cylindrical to receive and be engaged by the cylindrical oscillating valve 90 member 29. The opposite sides of the upper and lower sections 17 and 18 have laterally extending semi-cylindrical flanges 30 and 31, which are axially arranged, and surround the ends of the cylindrical valve 29. One 95 end of the valve 29 has an annular flange 32, and secured to the opposite end of the valve by means of the screws 33 is a circular plate or disk 34, which together with the flange 32, prevent axial movement of 100 said valve. This valve 29 has a transverse intake port 35, which is designed to constitute communication between the pneumatic chamber 24 and either of the hydraulic chambers 22 and 23, it depending upon the 105 position of the valve. In Fig. 2 the valve

is in such position that communication between the pneumatic chamber and the hydraulic chamber 22 is attained. The valve 29 is provided with exhaust ports or passages 36 and 37. The exhaust port or passage 36 is designed to exhaust the air from the chamber 23 while the port or passage is designed to exhaust the air from the chamber 22, it depending on the position of the valve. The circular disk or plate 34 is provided with openings 38 and 39, with which the passages or ports 36 and 37 register so that the air may exhaust to the atmosphere. Rising upwardly from the partition or bottom 20 on opposite sides of the bearing 28 are flanges or walls 40, to cover one or the other of the ports or passages 36 and 37 when out of communication with the respective chamber. A pipe 41 communicates the chamber 22 with the chamber 42 of the cylinder 7, and this pipe is provided with a valve 43 having an operating arm 44. A pipe 45 extends from the chamber 23 and communicates with the other end of the cylinder chamber 42. This pipe 45 has a valve 46, which is provided with an operating arm 47. Secured by a key or feather 48 on an extension 49 of the valve 29 is a lever 50, and connected to the arm 51 as at 52 is a pair of links 53 and 54. The link 53 is connected to the arm 44 as at 55 and the link 54 is connected to the arm 47 as at 56. The lower extremity of the arm 51 has a pin 57, which plays in the slot 58 of the link 59, which is pivoted at 60 to an arm 61 of a collar 62, which is adjustably secured on the piston rod 18 by means of the bolt or set screw 63. The upper arm 64 of the lever 50 has connected to it a rod 65. This rod 65 may be manually reciprocated, or may be operated by a lever (not shown). Suitable straining means 66 are provided in the chambers 22 and 23 for covering the exhaust ports and the intake port or passage 35, which is transversely of the valve. The cylinder chamber 42 is supplied with any suitable hydraulic means to the extent shown in the drawings, and air under pressure is admitted through the pipe 26 into the chamber 24, and in this case the air will pass through the port or passage 35 into the chamber 22, through the pipe 41 (the valve 43 having been opened) so as to force the hydraulic medium against the piston 8, operating the piston 8 to the position shown in Fig. 2, thereby operating the link motion mechanism so that the locomotive is capable of traveling straight ahead. After so operating the link motion mechanism, the rod 65 is reciprocated so as to position the valve 29 in a neutral position, in which case the intake port or passage 35 and the exhaust ports 36 and 37, and the valves 43 and 46 are closed. In order to reverse, the rod 65 is reciprocated so as to rock the valve 29,

whereby the port or passage 35 will communicate with the chamber 23. In this case air under pressure will enter the chamber 23, and pass through the pipe 45 (the valve 46 having been opened) and into the piston cylinder 42, forcing the hydraulic medium against the piston, reciprocating the same, and through the piston rod and link or pitman 3, the link motion mechanism will be reversed. In this operation the air previously used in the chamber 22 will exhaust out through the port 37.

The invention having been set forth what is claimed as new and useful is:—

1. In combination with a link motion, a reversing device for actuating the shifting lever of said link motion, said reversing device comprising a hydraulic cylinder, a piston reciprocating therein and having a rod connected with the shifting lever of the link motion, a chest on the cylinder having hydraulic chambers and a super-imposed pneumatic chamber, pipes of communication between said hydraulic chambers of the chest and the ends of the hydraulic cylinder, said pipes of communication having valves, an oscillating cylinder valve mounted in a bearing of the chest and having a port adapted, when the cylinder valve is oscillated, to put either of the hydraulic chambers in communication with the pneumatic chamber, whereby air may operate on the hydraulic means in either end of the hydraulic cylinder for reciprocating the piston, whereby the shifting lever of the link motion may be actuated, said cylinder valve having exhaust ports for exhausting the air from either of the hydraulic chambers of the chest, and connections between the cylinder valve and the valves of the pipes of communication for reversing said valves.

2. The combination with a link motion, of a reversing device for shifting the lever of said link motion said reversing device comprising a hydraulic cylinder, a piston reciprocating therein and having a rod connected with the shifting lever of the link motion, a chest on said cylinder having hydraulic chambers and a super-imposed pneumatic chamber, pipes of communication between said hydraulic chambers of the chest and the ends of the hydraulic cylinder, valves in said pipes, an oscillating cylinder valve in a bearing of the chest, said cylinder valve having a port adapted to put either of the hydraulic chambers in communication with the pneumatic chamber, whereby air may operate on the hydraulic means for forcing it into the hydraulic cylinder to operate the piston, whereby the shifting lever of the link motion may be actuated, a straining means in each of the hydraulic chambers for straining the pneumatic means, said cylinder valve having exhaust ports for exhausting air from either of the hydraulic chambers of

the chest, and lever and link connections between the cylinder valve and the valves of the pipes of communication for reversing said valves, said lever and link connections being connected with the piston rod of the piston.

In testimony whereof I have signed my

name to this specification in the presence of two subscribing witnesses.

BARNIE B. McENTIRE.
